Ifor R. Nicholas, Los Angeles, Calif.

Application January 1, 1944, Serial No. 112,149

Term of patent 7 years

(Cl. D26—1)

To all whom it may concern:

Be it known that I, Ifor R. Nicholas, a citizen of the United States, residing at Los Angeles, in the county of Los Angeles and State of California, have invented a new, original, and ornamental Design for a Magnetic Locating Tool or Similar Article, of which the following is a specification, reference being had to the accompanying drawing, forming a part thereof.

Figure 1 is a perspective view of a magnetic locating tool or similar article, showing my new design.

Figure 2 is a longitudinal, medial sectional view, and

Figure 3 is a transverse, sectional, the plane of section being indicated by the line 3—3 of Fig. 2 and the direction of view by the arrows.

I claim:

The ornamental design for a magnetic locating tool or similar article, substantially as shown.

IFOR R. NICHOLAS.
